UNITED STATES PATENT OFFICE.

PATRICK D. RIORDAN, OF NEW YORK, N. Y.

CLOTHES-DRIER.

1,354,421.

Specification of Letters Patent. Patented Sept. 28, 1920.

Application filed October 30, 1919. Serial No. 334,500.

To all whom it may concern:

Be it known that I, PATRICK D. RIORDAN, a citizen of the United States, and a resident of the city of New York, borough of 5 Manhattan, in the county and State of New York, have invented a new and Improved Clothes-Drier, of which the following is a full, clear, and exact description.

My invention has for its object to provide a clothes drier for use on lawns, court yards, verandas and similar places, where all parts of the drier are accessible to the operator. The construction is such that while the drier may be stored away in a very 10 small space when not in use, the drier, when set up in operative position, will support a number of articles of clothing.

The drier may be made of a very small size, so that it may be used as a toy clothes 20 drier, and this small clothes drier may be used by children not only as a means for drying dolls' and babies' dresses, but it may also be used as a doll's bed, rocker or swing.

Additional objects of the invention will 25 appear in the following specification in which the preferred form of my invention is described.

In the drawings similar reference characters refer to similar parts in all the views 30 in which—

Figure 1 is a plan view of my clothes drier in operative position.

Fig. 2 is a sectional view on the line 2—2 of Fig. 1;

Fig. 3 is a sectional view on the line 3—3 of Fig. 1;

Fig. 4 is a view showing the clothes drier folded so that it may be stored away in a very small space;

Fig. 5 is an enlarged sectional fragmentary view on the line 5—5 of Fig. 1;

Figs. 6 and 7 are fragmentary sectional views showing modified forms of means for holding the cord secured to the inner frame 45 in fixed position relatively to the outer frame.

By referring to the drawings, it will be seen that an open frame 10 is provided having a transverse upper member 11, sides 50 12 and a transverse bottom member 13, the bottom of the sides 12 extending below the transverse bottom member 13. Disposed below and pivoted to the transverse bottom member 13 there is a foot 14, which may be 55 folded in the same longitudinal plane with the frame 10 as shown in Fig. 4 of the

drawings, or may be disposed at right angles to the transverse bottom member 13, as shown in Figs. 1, 2 and 3 of the drawings. The sides 15 of the inner frame 16 are 60 pivoted intermediate of their ends to the sides 12 of the frame 10, the pivots being bolts 17, which are disposed through openings 18 in the side members 15 of the frame 16 and through openings 19 in the sides 12 65 of the frame 10, nuts 20 engaging the outer threaded ends of the bolts 17 to hold the bolts in place.

As best shown in Fig. 1 of the drawings, the ends 21 of the frame 16 have recesses 70 22 with orifices 23 leading to the recesses 22, through which is disposed the clothes line 24, this clothes line extending back and forth from one end 21 of the frame 16 to the said frame's other end, this being best 75 shown in the Figs. 1 and 4 of the drawings. The recesses 22 in the ends 21 of the frame 16 are closed by slats 25. The frame 16 may be disposed in a horizontal position as illustrated in Figs. 1, 2 and 3, so that the 80 clothes may be hung on the clothes line 24 to dry, but when it is desired to store the clothes drier away, the frame 16 may be folded in the longitudinal plane of the frame 10, as is shown in Fig. 4 of the drawings, 85 and the foot 14 may also be folded in the same longitudinal plane of the frame 10.

As a means of holding the frame 16 in a horizontal position, I employ a cord 26, the ends 27 of which are secured to the ends 21 90 of the frame 16, this cord 26 extending through an opening 28 in a bolt 29, which is preferably disposed through an opening 30 in the upper transverse member 11 of the frame 10. A washer 31 is disposed on the 95 bolt 29 and against the cord 26, and this washer may be pressed against the cord 26 by a nut 32 which will prevent the cord 26 from sliding through the opening 28 in the bolt and will, therefore, serve to hold the 100 frame 16 in an adjusted horizontal position. In some cases it will be desirable to secure the cord 26 at the bottom member 13 instead of at the upper transverse member 11, and in Fig. 7, I illustrate a modified construction, the cord 26 passing through an opening 28^a in the bolt 29^a, this bolt 29^a also serving as a pivot for the foot 14, the washer 31 and the nut 32 being the same construction as shown in Fig. 5 of the drawings.

In Fig. 6, I illustrate another means of

securing the cord 26, the cord in this figure passing through orifices 11^a in the upper transverse member 11, the cord 26 being engaged by a washer 32 mounted on a bolt 34, the bolt 34 being disposed in an opening 35 in the transverse upper member 11 and the washer 33 being pressed against the cord 26 at the orifices 11^a by a nut 36 mounted on the bolt 34.

10 As shown by the dotted lines in Fig. 2 of the drawings, a mattress or cushion may be disposed on the frame 16 and the lines 24, so that when the drier is made of a small size, it may be used with this mattress or cushion as a doll's bed, rocker or swing.

Having thus described my invention what I claim as new and desire to secure by Letters Patent is:—

20 1. In a clothes drier, an open frame, a second open frame smaller than the first frame and pivoted intermediate of its ends in the first frame, a clothes line carried by the second frame, a cord secured at its ends 25 to the second frame and means on the first frame to clamp the cord.

2. In a clothes drier, an open frame, a

second open frame smaller than the first frame and pivoted intermediate of its ends in the first frame, a clothes line carried by the second frame, a bolt secured to an end of the first frame and having a transverse opening, a cord extending through the opening and having its ends secured to the ends of the second frame and means 35 mounted on the bolt for engaging the cord to prevent its movement through the opening in the bolt.

3. In a clothes drier, a quadrilateral line-bearing frame pivotally mounted about 40 midway of its sides to and within a similarly constructed supporting frame about midway of its sides; the said line-bearing frame being rotatably suspended from the said supporting frame by a free roving 45 cord; means for guiding and clamping the said cord and thus fixing the said line-bearing frame in the horizontal or clothes-drying position; and adjustable means for securing the said supporting frame in the 50 standing or upright position, the pivotal mounting permitting the folding of the line-bearing frame within the supporting frame.

PATRICK D. RIORDAN.
